UNITED STATES PATENT OFFICE.

CHARLES G. SHEPARD AND PETER ADAMS, JR., OF BUFFALO, N. Y., ASSIGNEES TO SAID SHEPARD AND WALTER J. SHEPARD, OF SAME PLACE.

FLUTING-MACHINE.

SPECIFICATION forming part of Letters Patent No. 223,611, dated January 13, 1880.

Application filed May 13, 1878.

To all whom it may concern:

Be it known that we, CHARLES G. SHEPARD and PETER ADAMS, Jr., both of the city of Buffalo, in the county of Erie and State of New York, have invented a new and useful Improvement in Fluting-Machines, of which the following is a specification, reference being had to the accompanying drawings.

Our invention relates to that class of fluting-machines in which a corrugated bed-plate and a corrugated roller are employed. In this class of fluting-machines it is desirable that the handle of the roller should be so arranged that a direct pressure can be brought to bear upon the roller.

The object of our invention is the construction of a simple and cheap fluting-roller of this character; and it consists in the particular construction of the device, as will be herein-after fully set forth.

In the accompanying drawings, Figure 1 is an end elevation of our improved fluting-roller. Fig. 2 is a longitudinal section thereof.

Like letters of reference designate like parts in both figures.

A represents the cylindrical body of the fluting-roller, provided on its periphery with teeth or corrugations, in the usual form. B B are the end plates of the roller, and C C are short journals arranged centrally on the end plates, E is a bifurcated or U-shaped bar, which straddles the fluting-roller and is sprung over the journals C, its ends being provided with openings, in which the journals revolve. E' is

a shank arranged centrally on the bifurcated bar E and in the same plane with the same. F is the handle proper, consisting of a single bar secured at its center to the shank E', at right angles thereto and in a plane which intersects the axis of the roller at right angles. The handle-bar F is preferably cast hollow, and the shank E' constructed with a reduced top portion, which projects through the handle-bar and is riveted over at the upper side thereof, whereby the handle-bar is firmly and cheaply secured to the shank.

This construction and arrangement of the handle renders the device very simple and durable, and at the same time enables the roller to be more conveniently operated than ordinary rollers, and permits the pressure to be exerted upon the roller directly by placing the hand centrally above the roller, whereby a better impression is produced on the fabric without requiring an unusual effort on the part of the operator.

We claim as our invention—

The combination, with the fluting-roller A, provided with journals C C, of the bifurcated or U-shaped bar E, central shank, E', and the single handle-bar F, secured at its middle to the shank E', at right angles therewith, and extending across the bar E and the roller.

CHARLES G. SHEPARD.

PETER ADAMS, JR.
